DESIGN FOR AN AUTOMOBILE

Raymond G. F. Loewy, New York, N. Y.

Application January 18, 1937, Serial No. 67,111

Term of patent 7 years

To all whom it may concern:

Be it known that I, Raymond G. F. Loewy, a citizen of the Republic of France, residing at New York city, county of New York, and State of New York, have invented a new, original, and ornamental Design for an Automobile, of which the following is a specification, reference being had to the accompanying drawing, forming part thereof.

The characteristic features of my design reside in the hood, radiator sections and the headlights associated therewith.

I claim:

The ornamental design for an automobile as shown and described.

RAYMOND G. F. LOEWY.
